UNITED STATES PATENT OFFICE.

HERBERT R. AYERS AND CHARLES A. DORR, OF LYNDHURST, NEW JERSEY.

SIGNAL.

1,182,618.

Specification of Letters Patent.

Patented May 9, 1916.

Application filed March 16, 1915. Serial No. 14,806.

To all whom it may concern:

Be it known that we, HERBERT R. AYERS and CHARLES A. DORR, both residents of Lyndhurst, in the county of Bergen and State of New Jersey, have invented an Improvement in Signals, of which the following is a specification.

Our invention relates generally to signals, and more particularly to what we are pleased to term a disappearing signal.

As is generally known, it is customary, when turning aside or rounding corners, or lessening the speed of a motor vehicle for the driver, or some one in the car, to extend his hand and arm to indicate to those who may be in the rear that he is about to change his course or speed, as hereinbefore indicated. When the hand and arm of the driver are used for this purpose, the car must be controlled entirely with the other hand, and this, in some instances at least, is not only difficult, but likely to lead to accidents.

The object of our invention, therefore, is the provision of a signal which is so light, compact, inexpensively constructed, and easily operated, as to be applied to motor vehicles for a signal to indicate to those behind that the car is about to turn, change its course, or stop. While particularly adapted for this purpose, it is to be understood, however, that the signal made in accordance with our invention may be utilized for other purposes, in divers places, and in any and all places, and for any and all uses to which it may be found adaptable.

In carrying out our invention, we preferably employ a casing open at one side and provided with a cover, together with a plurality of signal arms, one of which is attached to the cover and may be actuated through suitable mechanism with the cover, so that through these parts other signal arms may be moved from a nested position within the casing to an operative position, and then returned to the nested position in the casing, in which they are invisible, and where they remain when not in use, as will be hereinafter more particularly described.

In the drawing, Figure 1 is a rear elevation of a disappearing signal made in accordance with our invention. Fig. 2 is a side elevation of the same, with the signal arms in their operative positions, and Fig. 3 is a partial front elevation with the parts in the position shown in Fig. 2.

Referring particularly to the drawing, our improved disappearing signal preferably comprises a casing made with three sides 10, 11, and 12, suitably connected to each other and provided with a cover 13 for the fourth side of the casing. The casing may also be provided with a cap 14, and may be secured to an extension 15 of a bracket 16, or otherwise. As indicated in the drawing, the extension 15 is secured to the rear member 11 of the casing by a clamp 17, and the bracket 16 is secured to a support 18 by screws or rivets. It will be understood, however, that the casing may be supported in any desired manner and connected to any suitable support without departing from the nature and spirit of our invention. We also employ a series or plurality of signal arms. One of these arms 19, is indicated at 19, and is preferably angular, one web of which is made to lie flush against the under or inner side of the cover 13 and is secured thereto in any suitable manner. At one end, the arm 19 is provided with a pivot 20, extending between and journaled in the opposite sides of the casing, so as to pivotally mount the arm 19 therein. Extending beyond the pivotal point of the arm 19, the same is fitted with a lever 21, which, as indicated, passes through the rear wall of the casing, for the purpose hereinafter explained. The other signal arms are indicated at 22, 23, and 24, and at corresponding ends these arms are provided respectively with pivots 25, 26 and 27, each of which is journaled in one side member of the casing so that each signal arm is pivotally mounted in the casing independently of the other signal arms. At their opposite ends, the signal arms are connected by links.

As indicated in the drawing, a link 28 is pivotally connected to the arms 19 and 22, as indicated at 29. A link 30 is pivotally connected to the arms 22 and 23, as indicated at 31, and a link 32 is pivotally connected to the arms 23 and 24, as indicated at 33. It will be apparent from this construction that by raising or swinging the arm 19 and cover 13 on the pivot 20, that the arms 22, 23 and 24 will be caused to move in unison therewith. Also by reference to Fig. 3, it will be apparent that these arms, being spaced across the compartment within the casing, are adapted to lie therein in a nested condition, and the construction is such that when these signal arms lie

within the casing the cover 13 closes the otherwise open side thereof so as to completely incase the signal arms. We have also illustrated in the drawing one form of mechanism for operating the signal arms, although, as will be understood, any suitable mechanism may be employed and it may be necessary to vary the construction of this operating mechanism, depending upon 10 the position in which the signal is placed and the use to which it is put.

As will be seen in the drawing, the operating mechanism disclosed includes a lever 34 pivotally connected at 35 in the bracket 16, and passing through an aperture provided therefor in a lug 36 turned out from one side of the bracket. In this lug there is a shoulder 37, against which the lever 34 may engage, as hereinafter explained, to 20 maintain the signal arms in an open position for use. This operating mechanism also includes a lever 38, pivoted in the bracket 16 at 39, and connected to the lever 34 by a link 40, a pivotal connection with 25 the lever 34 being indicated at 41, and a similar connection with the lever 38 being indicated at 42. The free end of the lever 38 is connected to the end of the lever arm 21 by a rod 43, and in order to insure the 30 signal arms being maintained positively within the casing, when not in use, we prefer to employ a spring 44 at its ends connected to and extending between the clamp 17 and the free end of the lever 34. This 35 spring, as will also be understood, insures a quick return of the parts to their positions in the casing when the lever 34 is released from the shoulder 37.

Normally, the signal arms lie within the 40 casing and the levers and links assume the position shown in Fig. 1. To operate the parts and set the signal, it is only necessary,

in the structure as shown and described, to depress the lever 34 and pass the same under the shoulder 37. This will move the 45 levers and links from the positions shown in dotted lines in Fig. 1 to those shown in full lines, and will swing the signal arm 19 and the cover 13 to the position shown in Fig. 2, these parts carrying with them the other 50 signal arms. The signal arms, furthermore, will be maintained in this position until the lever 34 is moved from its position against the shoulder 37, when by gravity, assisted by the action of the spring 44, the signal 55 arms will return to their nested positions within the casing, with the cover 13 closing the otherwise open side thereof. We may also employ a strip of rubber or felt 45 lying against the inner surface of the rear member of the casing, and against which, when in their nested positions in the same, the signal arms are caused to bear, in order to overcome or prevent any possible movement of the parts, due to vibration, and consequently any objection due to the rattle of the car from such movement.

We claim as our invention—

A signal comprising a casing open at one side, a signal arm pivoted at one end in the 70 said casing, a plate secured to said arm and adapted to provide a cover for the open side of the casing, a plurality of signal arms each pivoted at one end in one side of said casing and adapted to fit within the same 75 in a nested position, and links extending between and pivoted to the free ends of adjacent signal arms for connecting, supporting and spacing the same.

Signed by us this 12th day of March, 86
1915.

HERBERT R. AYERS,
CHARLES A. DORR.
